UNITED STATES PATENT OFFICE.

REGINALD G. SMITH AND EARL N. PERCY, OF OAKLAND, CALIFORNIA.

ORCHARD-HEATER.

1,077,009.

Specification of Letters Patent. Patented Oct. 28, 1913.

Application filed July 30, 1913. Serial No. 781,975.

To all whom it may concern:

Be it known that we, REGINALD G. SMITH, a subject of the King of England, and EARL N. PERCY, a citizen of the United States, residing at Oakland, in the county of Alameda and State of California, have invented new and useful Improvements in Orchard-Heaters, of which the following is a specification.

10 This invention relates to orchard heaters, and pertains especially to a novel, simple means for effecting a down draft upon and over the oil fuel to effect perfect combustion.

15 The invention consists of the parts and the construction and combination of parts as hereinafter more fully described and claimed, having reference to the accompanying drawings, in which—

20 Figure 1 is a vertical section on line X—X of Fig. 2. Fig. 2 is a cross section on line Y—Y of Fig. 1.

A is a liquid fuel containing receptacle of suitable size and shape having a tight fitting 25 cover 2, provided with a gas outlet 3. Suitably supported on the cover and extending upwardly therefrom and surrounding the gas outlet 3 is a short inner stack 4 which is closed at the top by a cowl plate 5 for the 30 purpose of directing the gases generated within the receptacle radially outward through a series of small perforations 6 which are made around the top of the inner stack.

35 7 is an outer stack spaced from the inner stack and circumferentially supported on the cover extending considerably above the closed or choked end of the inner stack having a series of perforations 8 around its 40 base. The regulation of air through the holes 8 is accomplished by a perforated sleeve damper 9.

45 10 is a cover vent in the cover, primarily designed for ignition purposes and also serving as an air duct for admitting air into the receptacle.

A novel feature of the present invention is the use of an external air tube 11 which is adapted to telescope with a flange 12 50 which surrounds the air inlet 13 in the cover. This tube 11 projects outwardly from the cover and is of sufficient length and size and is so positioned that under the influence of the draft induced through the stack 7 a current of air will be drawn in through tube 11 and swept downwardly in a direction to

ward the bottom of the receptacle and commingled with the gases evolved or generated within the receptacle, and close to the surface of the liquid fuel. The two tubes 7 and 11 act in conjunction and as an inverted siphon to draw the air into the receptacle and imparts the desired velocity to the air. The tube imparts direction to the air currents so that the inertia of the incoming air being at a sufficient velocity and directed in a definite direction is carried to the surface of the oil and finally to the bottom of the pot as the oil recedes, thus enabling the heater to be burned out clean.

The sizes and proportions of a particular heater of this sort would be approximately as follows: Pot—6" deep—16" inside bottom diameter and 18" inside top diameter, with cover to fit. Outside stack 7—approximately 6" in diameter at the base and 24" high. Air inlet 13—3" in diameter. Air draft regulating tube 11—approximately 2" in length.

The essential feature of the invention is 80 that the air inlet tube 11 is of such proportions with respect to the stack and points in a direction toward which the air currents are to be directed within the receptacle so that the up draft in the comparatively tall 85 stack 7 will induce a down draft in the tube 11 and give such velocity to this down draft that will cause the air to sweep across the receding oil to produce the proper combustible mixture.

Having thus described our invention what we claim and desire to secure by Letters Patent is—

1. In an orchard heater, the combination 90 of a liquid fuel containing receptacle having a close fitting cover, said cover having a gas outlet and a combustible stack in conjunction therewith, and an exterior tube carried by the cover and projecting outwardly therefrom and opening into the receptacle and 95 with its axis pointing in the direction of the bottom of the receptacle, said tube of less length and smaller diameter than the stack whereby the up draft through the stack induces a down draft through the tube so that 100 the incoming air sweeps across the surface of the oil in the receptacle.

2. In an orchard heater, the combination 105 of a fuel containing receptacle having a close fitting cover, said cover having a stack on its exterior and opening into the receptacle, said stack provided with perforations

around its base, an exterior air draft tube carried on the outside of the cover and projecting outwardly and away therefrom, and opening downwardly into the receptacle, 5 said outwardly projecting air tube being shorter than the stack, the stack and tube constructed and arranged to create by the updraft through the stack a down-draft through the tube and into the receptacle, 10 said tube having a regulating damper and

said stack having a damper controlling the aforesaid perforations therein.

In testimony whereof we have hereunto set our hands in the presence of two subscribing witnesses.

REGINALD G. SMITH.
EARL N. PERCY.
